UNITED STATES PATENT OFFICE.

SIDNEY HAWARD, OF CHISWICK, LONDON, ENGLAND, ASSIGNOR TO WITCOMBE, McGEACHIN AND COMPANY, OF NEW YORK, N. Y.

DESIGN FOR AN ARTICLE OF MANUFACTURE.

52,479.

Specification for Design.

Patented Sept. 24, 1918.

Application filed March 4, 1918. Serial No. 220,406. Term of patent 3½ years.

To all whom it may concern:

Be it known that I, SIDNEY HAWARD, a subject of the King of Great Britain, residing at Woodstock Corner, Bedford Park, Chiswick, London, England, have invented an ornamental Design for an Article of Manufacture, of which the following is a specification, reference being had to the accompanying drawing, forming part thereof.

The figure is a plan view of a printed fabric showing an embodiment of my new design. It is to be understood, however, that my new design may be applied not only to fabrics, but also to wall paper, wrapping paper, or similar articles having surface ornamentation, without departing from what I claim as my invention.

I claim:—

The ornamental design for an article of manufacture, substantially as shown and described.

SIDNEY HAWARD.
